(57) CLAIM

I claim the ornamental design for a wall hung toilet, as shown and described.

DESCRIPTION

FIG. 1 is a perspective view of an embodiment of the claimed design;

FIG. 2 is a front view of the claimed design shown in FIG. 1;

FIG. 3 is a rear view of the claimed design shown in FIG. 1;

FIG. 4 is a top view of the claimed design shown in FIG. 1;

FIG. 5 is a bottom view of the claimed design shown in FIG. 1;

FIG. 6 is a side view of the claimed design shown in FIG. 1;

FIG. 7 is a side view of the claimed design shown in FIG. 1;

FIG. 8 is a perspective view of another embodiment of the claimed design;

FIG. 9 is a front view of the claimed design shown in FIG. 8;

FIG. 10 is a rear view of the claimed design shown in FIG. 8;

FIG. 11 is a top view of the claimed design shown in FIG. 8;

FIG. 12 is a bottom view of the claimed design shown in FIG. 8;

FIG. 13 is a side view of the claimed design shown in FIG. 8; and,

FIG. 14 is a side view of the claimed design shown in FIG. 8.

In the drawings, the broken lines depict unclaimed portions of the wall hung toilet. The dot and dashed lines represent a boundary between the claimed and the non-claimed portions and form no part of the claimed design.
